Lewis F. Platt, Atlanta, Ga., assignor to Scripto, Inc.,
a corporation of Georgia

Filed Oct. 9, 1958, Ser. No. 52,916

Term of patent 14 years

(Cl. D74—17)

Fig. 1   *Fig. 2*   *Fig. 3*

Fig. 4   *Fig. 5*   *Fig. 6*

Fig. 1 is a side elevational view of a ball point pen embodying my new design;

Fig. 2 is a rear elevational view thereof;

Fig. 3 is a front elevational view;

Fig. 4 is a horizontal sectional view taken on the line 4—4 of the ball point pen shown in Fig. 1;

Fig. 5 is a top plan view of Fig. 2; and

Fig. 6 is a horizontal sectional view taken on the line 6—6 of Fig. 3.

The dotted lines in Figs. 4 and 6 indicate that parts of the interior have been omitted for convenience of illustration.

I claim:

The ornamental design for a ball point pen, as shown and described.
